UNITED STATES PATENT OFFICE.

WILLIAM FRASER, OF STOCKHOLM, SWEDEN, ASSIGNOR TO WYCKOFF, SEAMANS & BENEDICT, OF ILLION, NEW YORK, A CORPORATION OF NEW YORK.

TYPE-WRITING MACHINE.

No. 842,396.

Specification of Letters Patent.

Patented Jan. 29, 1907.

Application filed April 22, 1905. Serial No. 256,978.

To all whom it may concern:

Be it known that I, WILLIAM FRASER, a subject of the King of Sweden and Norway, and a resident of Stockholm, in the Kingdom of Sweden, have invented certain new and useful Improvements in Type-Writing Machines, of which the following is a specification.

My invention relates to connecting devices, and more particularly to connecting devices for type-writing machines; and the object of said invention is to provide a simple and efficient means which afford a ready connection of or disconnection between the parts when desired, and in which the parts are not liable to become accidentally detached in use.

While I have shown my invention applied to a connecting-link between a key-lever and type-bar of a type-writing machine, it should be understood that the invention may be applied to various parts and various styles of type-writing machines, and, in fact, may be employed in any kind of machine in which the use of the connecting device may be found available.

To the above and other ends, which will hereinafter appear, my invention consists of the features of construction and arrangements and combinations of parts to be hereinafter described and claimed.

In the accompanying drawings, Figure 1 is a fragmentary front to rear sectional view showing sufficient number of parts of a type-writing machine to illustrate my invention in its application thereto. Fig. 2 is a fragmentary detail front elevation of one form of connecting device embodying my invention, the end of the type-bar to which the connecting device is connected being shown in section; and Fig. 3 is a detail side elevation of the connecting device.

A key-lever 1 is fulcrumed at 2 in the base of the machine and is provided with the usual finger-key 3 and restoring-spring 4. A metal band or strap 5 surrounds the key-lever and extends above it, as at 6, and is perforated to form a connecting-eye. A connecting-link 7 is in the nature of a two-part link made up of upper and lower members 8 and 9, respectively, which are adjustably united by a turn-buckle 10 with internal oppositely-cut threads to co-operate with the external threads on the members 8 and 9. Either the upper end

or both ends of the link may be provided with connecting devices embodying my invention. 55 In the present instance I have shown both ends of the link provided with such devices, the lower device affording means for detachably and pivotally connecting the link to the eye 6 on the key-lever, whereas the upper end 60 of the link is provided with such a device for detachably and pivotally connecting the upper end of the link to the short arm 11 of a type-bar 12, pivoted at 13 to a type-bar hanger 14, so that a depression of the key- 65 lever will move the type-bar to printing position.

The connecting device at both ends of the link is the same, so that the description of one will apply to the other. An end of the connecting link or member to be pivotally and detachably connected to its associated part is provided with a laterally-projecting pivot pin or hook 15, that may be formed by bending the end of the link at substantially right angles to its length, as shown in Fig. 2. This part is seated in an opening or eye of the part to which the link is to be connected—as in the eye 6, for instance—on the key-lever or in the opening 16 in the short arm 11 of the type- 80 bar.

A retaining device or leaf-spring 17 may be attached to the link in any suitable manner, as by forming a split barrel-like securing portion 18 from the spring at one end and clamping the securing portion around the link and fixing it in place by solder. The spring itself comprises two portions 19 and 20, the planes of which are at right angles or substantially right angles to each other, the spring being 90 twisted at 21 to effect this end. The short portion 20 constitutes a securing or bearing member that is adapted to bear on the free end of the pivot or hook 15 to prevent the accidental detachment of the type-bar or the other member that is connected by the device. The short extent of metal forming the portion 20 makes it stiff, so that there is little or no resiliency between the terminal of the portion 20 and the bend 21, and it cannot be 100 deflected in the direction of the arrow in Fig. 2. The part 19 is long when compared with the part 20, affording considerable resiliency at this portion of the device, so that it may readily receive a flatwise deflection, or a deflection in the direction of the arrow in Fig. 3,

though it cannot be moved edgewise or in the direction of the arrow in Fig. 2. The part 19 is alined with the body of the link, so that the link constitutes a stop to limit or prevent a movement of the spring in a direction opposite to that indicated by the arrow in Fig. 3.

From the foregoing it will be seen that the spring-retaining device is normally maintained by the spring tension thereof in the locking position shown and that it is rigid against deflection or displacement in the direction of the axis of the pivot 15, or in the direction of the arrow in Fig. 2; and that it is only by a relative movement in this direction between the link and the type-bar that the parts can be disconnected, and therefore the parts are positively locked against accidental disconnection. On the other hand, when it is desired to effect a disconnection between the parts it is merely necessary to deflect the retaining device against the tension of its spring that is exerted at right angles to the axis of the pivot 15, or, in other words, to deflect the retaining device in the direction of the arrow in Fig. 3, which will result in moving the portion 20 away from and to one side of the end of the pivot 15 and the parts may readily be disconnected. It will also be seen that the plane of the spring body portion 19 of the retaining device is coincident with or parallel to the pivot 15.

It will be observed that by my invention I have provided simple, cheap, and efficient means for positively preventing the accidental disconnection between two pivotally-connected parts and that the parts may nevertheless be readily disconnected when desired.

While I prefer to make 18, 19, and 20 of each retaining device of a single piece, they may be made of more than one piece, and the connecting devices may be made in any suitable manner to suit the conditions or the particular application of the devices, and various changes may be made without departing from the spirit of my invention.

What I claim as new, and desire to secure by Letters Patent, is—

1. In a device of the character specified, the combination of a member having a pivot, and a retaining device that coöperates with an end of the pivot to prevent the part seated thereon from being accidentally displaced lengthwise of the pivot and detached therefrom, said retaining device being prevented from moving in the direction of the axis of the pivot and being adapted to be deflected in a direction at substantially right angles thereto and to permit a lengthwise withdrawal of the pivot.

2. In a device of the character specified, the combination of a member having a pivot, and a spring retaining device that coöperates with an end of the pivot to prevent the part seated thereon from being accidentally detached, said retaining device being prevented

from moving in the direction in which said part is unseated from the pivot and which may be deflected against its spring-pressure in another direction to free said part.

3. The combination of a pivot, a coöperating member with a hole through which the pivot may be projected endwise, and a retaining device comprising a leaf-spring that coöperates with an end of the pivot, the plane of the spring body portion of said leaf-spring being coincident with or parallel to the pivot.

4. The combination of a member having a laterally-projecting pivot, and a retaining device, said retaining device comprising a leaf-spring with the plane of one portion thereof at substantially right angles to the plane of another portion thereof.

5. The combination of a member having a laterally-projecting pivot, and a retaining device, said retaining device comprising a leaf-spring with the plane of one portion thereof at substantially right angles to the plane of another portion thereof, and one of said portions being resilient and the other substantially non-resilient.

6. The combination of a member having a laterally-projecting pivot, and a retaining device, said retaining device comprising a leaf-spring with the plane of one portion thereof at substantially right angles to the plane of another portion thereof, and one of said portions being resilient and the other substantially non-resilient, the plane of the resilient portion being coincident with or parallel to the pivot and the plane of the non-resilient portion being at substantially right angles to the axis of the pivot.

7. The combination of a member having a laterally-projecting pivot extending therefrom, and a leaf-spring that is secured thereto and coöperates with the free end of the pivot to prevent the accidental disconnection of the device seated on said pivot, said spring being fixed against yielding in the direction of the axis of the pivot and adapted to yield in a direction at substantially right angles thereto.

8. The combination of a member having a laterally-projecting pivot extending therefrom, and a leaf-spring that is secured to said member and coöperates with the free end of the pivot to prevent the accidental disconnection of the device seated on said pivot, said spring being bent in planes at right angles to each other at opposite end portions, one end being secured to said member and the other bearing on the free end of the pivot.

9. The combination of a member having a laterally-projecting pivot extending therefrom, a leaf-spring that is secured to said member and coöperates with the free end of the pivot to prevent the accidental disconnection of the device seated on said pivot, said spring being bent to form two members in planes at substantially right angles to each

other, one member being resilient and the other substantially non-resilient, and means for securing the end of the resilient member to the pivot-carrying member whereas the 5 substantially non-resilient member coöperates with the free end of the pivot.

10. A link bent at one end thereof to form a pivot, and a retaining device coöperating with the free end of said pivot to prevent the 10 accidental disconnection of the member seated thereon, said retaining device comprising a leaf-spring having portions 19 and 20 bent at 21 so that the planes thereof are at

right angles to each other, the portion 20 being comparatively short whereas the other 15 portion 19 is comparatively long, the long portion 19 being secured to the link and the part 20 coöperating with the end of the pivot.

Signed at Stockholm, in the county of Stockholm and Kingdom of Sweden, this 7th 20 day of April, A. D. 1905.

WILLIAM FRASER.
